C. B. KING, C. B. WESTON & G. HOLMES.
SPACER FOR DIPPER HANDLES.
APPLICATION FILED OCT. 25, 1913.

1,128,152.

Patented Feb. 9, 1915.

UNITED STATES PATENT OFFICE.

CHARLES B. KING AND CLARENCE B. WESTON, OF MARION, OHIO, AND GRANT HOLMES, OF DANVILLE, ILLINOIS, ASSIGNEES TO THE MARION STEAM SHOVEL COMPANY, OF MARION, OHIO, A CORPORATION OF OHIO.

SPACEES FOR DIPPER-HANDLES.

1,128,152.

Specification of Letters Patent.

Patented Feb. 9, 1915.

Application filed October 25, 1913. Serial No. 797,221.

To all whom it may concern:

Be it known that we, CHARLES B. KING and CLARENCE B. WESTON, both residing at Marion, in the county of Marion and State 5 of Ohio, and GRANT HOLMES, residing at Danville, in the county of Vermilion and State of Illinois, citizens of the United States, have invented certain new and useful Improvements in Spacers for Dipper- 10 Handles, of which the following is a specification, reference being had therein to the accompanying drawings.

This invention relates to a spacer for a dipper handle such as is commonly employed in connection with steam shovels and similar excavating machines. In excavating machines of this type a long boom is employed which comprises two members spaced apart and adapted to receive between them 15 a dipper handle which also comprises two members. These booms and dipper handles, particularly in the larger sized machines, are quite long and the capacities of the dippers are large. Consequently when lateral 20 or swinging movement is imparted to the boom, to move the dipper from the point of excavation to the point of dumping, considerable force is required to overcome the 25 inertia of the dipper and its load. As a result of the force thus applied there is a tendency to spring the members of the dipper handle inward at their point of intersection with the boom. This inward springing of the handle members eventually produces a permanent inward curve and 30 permits slight lateral play of the handle. This play causes a hammering and consequently a rapid increase of the inward bend of the handle which in time becomes so great as to 35 not only weaken the handles but materially interfere with their operation. The construction of the mechanism is such that it is highly desirable to employ spaced members in constructing the dipper handle and for 40 this reason it is not practical to place permanent spacing blocks between the members of the handle.

The object of the present invention is to 45 provide means for spacing apart and thus reinforcing the dipper handle without the introduction of spacing blocks permanently secured between the handle members.

In the accompanying drawings, Figure 1

is a longitudinal, sectional view of a boom showing our invention applied thereto; Fig. 55 2 is a sectional view taken on the line α α of Fig. 1 and looking in the direction of the arrows; and Fig. 3 is a detail view of the connection between the spacing bar and the boom. 60

In carrying out our invention we provide a bar of a thickness substantially equal to the space between the two members of the dipper handle. This bar is extended between the two members of the handle, 65 parallel with the boom, and secured at its ends to the boom. The bar is arranged near the lower edge of the boom, at the point where the handle is brought into contact with the boom. This bar may be of any 70 suitable kind and may be secured to the boom in any suitable manner, the construction and arrangement herein shown being chosen for the purpose of illustration only.

In the present instance the invention is 75 shown as applied to a boom of a well known construction comprising two side members, 1, spaced apart and provided with inclined fillers 2 arranged on opposite sides of the point of support for the dipper handle and 80 converging upwardly toward the shipper shaft 3 which is mounted on the boom. The dipper handle 4 extends between the two members of the boom and comprises spaced members each having on its lower edge a 85 toothed rack 5 which meshes with pinions 6 on the shipper shaft 3. A yoke 7 extends between the two members of the handle and carries rollers 8 which bear on the upper edges of the handle and tend to hold the 90 racks in mesh with their pinions. This construction and its operation are well known and need not be gone into in detail here. In order to reinforce the handle and prevent the two members thereof from springing 95 inward we have arranged a spacing bar 9 between and along the lower edges of the two members 1 of the boom and have connected the same at its opposite ends with the boom. This spacing member is arranged 100 centrally of the space between the boom members and extends also between the two members of the handle, the thickness of the spacing member 9 being substantially equal to the space between the handle members, 105 there being just enough play to allow the

handle to work freely between the boom members. The spacing bar or member will be secured to the boom in any suitable manner but in the present instance we have provided it with forwardly extending arms 10 which are connected at their upper ends, by means of pins 11, with bearing members or blocks 12 secured to the respective fillers 2. It will be apparent that with this construction the dipper handle can be moved longitudinally to move the dipper toward or away from the boom or it can be swung about the axis of the shipper shaft to move the dipper toward and away from the end 15 of the boom and in any position it may assume during these movements the spacer bar will lie between those portions of the handle members which are in a position to engage the respective edges of the adjacent 20 boom members. As a result, when one member of the handle is brought into engagement with the edge of the adjacent boom member the strain is not imposed solely upon this member but is transmitted 25 through the spacing member 9 to the second handle member. Consequently, both members of the handle receive a share of the strain imposed upon the handle and the combined strength of the two members will 30 oppose the bending of that member which is in contact with the boom. The tendency to spring inward is also resisted and prevented by the spacing bar. The construction and arrangement of this spacing bar 35 practically eliminates the difficulties which have heretofore been experienced in connection with dipper handles due to the springing of the members.

While we have shown and described one embodiment of our invention it will be understood that this has been chosen for the purpose of illustration only and that we do not desire to be limited to the details of construction shown and described, for obvious modifications will occur to a person skilled in the art.

Having thus fully described our invention, what we claim as new and desire to secure by Letters Patent, is:—

1. The combination, with a boom comprising spaced members, a dipper handle also comprising spaced members, and a support for said dipper handle near one edge of said boom, of a spacing device supported by 50 said boom near the other edge thereof and extending between the members of said dipper handle.

2. The combination, with a boom comprising spaced members, and a dipper handle 55 also comprising spaced members, of a spacing bar extending longitudinally of said boom, connected at its ends thereto and extending between the two members of said handle.

3. The combination, with a boom com-

prising spaced members, and a dipper handle also comprising spaced members, of a spacing bar permanently secured at its ends to said boom, extending longitudinally of the boom near the lower edge thereof and 70 extending between the two members of said dipper handle.

4. The combination, with a boom comprising two members spaced apart, fillers arranged between said members of said boom, 75 a dipper handle extending between the two members of said boom and between said fillers, said handle comprising two members spaced apart, of a spacing bar extending between said members of said handle, arranged longitudinally of said boom near the lower edge thereof and having upturned portions connected to the respective fillers. 80

5. The combination, with a boom comprising two members spaced apart, of a dipper handle also comprising two members spaced apart, said handle being mounted upon said boom near one edge thereof for longitudinal and swinging movement, a spacing device carried by said boom near the other edge 90 thereof and between the ends thereof and arranged to extend between the two members of said handle in any position in which said handle may be placed by either of said movements. 95

6. The combination, with a boom, a dipper handle comprising spaced members, of a spacing device extending between the members of said dipper handle and connected with said boom on opposite sides of said handle. 100

7. The combination, with a boom, and a dipper handle comprising spaced members capable of both longitudinal and swinging movements, of a spacing device extending 105 between the members of said dipper handle, supported on opposite sides of said handle by said boom, and arranged to space said members apart when said handle is in any position in which it may be placed by either 110 of said movements.

8. The combination with a boom comprising spaced members, and a dipper handle also comprising spaced members, of a spacing device supported along the lower edge 115 of said boom between the ends thereof and extending between the members of said dipper handle.

9. The combination with a boom comprising two members spaced apart, of a dipper 120 handle also comprising two members spaced apart, said handle being mounted on said boom for longitudinal and swinging movements, a spacing device supported in fixed relation to said boom and arranged to extend between the two members of said handle in any position in which said handle may be placed by either of said movements. 125

10. The combination, with a boom comprising spaced members, and a dipper han- 130

- dle also comprising spaced members, said dipper handle being pivotally mounted on the upper edge of said boom, of a spacing device mounted near the lower edge of said 5 boom between the ends thereof and extending lengthwise of the boom between the members of the boom and between the members of the dipper handle.
11. The combination, with a boom comprising two members spaced apart, a dipper handle also comprising two members spaced apart, said handle being mounted upon said boom between the ends thereof and extending transversely to the boom and between 10 the members thereof, and an actuating device mounted near the upper edge of said boom and forming a fulcrum for said dipper handle, of a spacing device supported by said boom near the lower edge thereof 15 and arranged to extend between the members of said handle at a point adjacent to 20
- said boom in any position which the handle may assume during its normal operation.
12. The combination with a boom comprising spaced members and a dipper handle 25 also comprising spaced members, of a spacing device supported by and between the ends of said boom and extending between the members of said dipper handle.
